UNITED STATES PATENT OFFICE.

GEORGE F. BEEBE AND WALTER O. BEEBE, OF HORNELLSVILLE, ASSIGNORS
OF ONE-THIRD OF THEIR RIGHT TO CHAS. M. WOODS, OF NEW YORK, N. Y.

PUMP.

SPECIFICATION forming part of Letters Patent No. 226,018, dated March 30, 1880.

Application filed February 26, 1880.

To all whom it may concern:

Be it known that we, GEORGE F. BEEBE and WALTER O. BEEBE, citizens of the United States, residing at Hornellsville, in the county of Steuben and State of New York, have jointly invented certain new and useful Improvements in Pumps; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Our invention consists of a novel construction of a double-acting pump having valveless pistons and open cylinders, acting either as a suction, a submerged, or a force pump, and also in certain new devices and combinations, all of which will be understood by the following description.

In the accompanying drawings, Figure 1 is a vertical section of our improved pump on the line of the working level. Fig. 2 is a transverse section. Fig. 3 is an enlarged view of the cylinders, pistons, and valves. Fig. 4 is a detached view of the stud for the pump to rest upon in the bottom of the well. Figs. 5 and 6 are views of the ball-valves, valve-seats, and packings.

The double-way pipes A A' and B B' are cast in one piece. They have an easy curve, in the form of an inverted arch, thus giving a free flow to the water. This casting is very compact, and coupled centrally below to the pipe C and above to the pipe G. It is cast with hubs a a', to receive the valve-seats, packing, and lower ends of the hollow cylinders F F'.

When the valve-seats, packing, and lower ends of the cylinders are put into these hubs the cap H is pressed down upon the tops of the cylinders by means of the single nut I, thus fastening the parts and packing the valves and lower ends of the cylinders in the hubs a a'. This cap H acts as a guide to the piston-rods K.

By this construction my pump may be placed at different heights above the water, or submerged at pleasure, by simply changing the

length of the pipe C and pipe G, and also the piston-rods K K, to suit the purpose desired.

At the lower end of pipe C we employ a short stud, D, for the pump to rest upon and for drawing the water all out of the well; but for drawing clear water only we substitute a longer stud, D'.

The central discharge-pipe, G, is provided with an air-chamber, L, which is spherical, or nearly so, this being the best form for an air-chamber.

The lever M, for working the pump, has its fulcrum N on the air-chamber, and is provided with connecting-rods O, attached to the piston-rods, which are prevented from side sway and made to run true by means of the guideways 60 in the ends of the cap.

The piston-cylinders F F' are cast without any flanges and fastened in place by means of the cap H, pressed down by the nut I, thus packing the bottom of the cylinders and valve-seats in the hubs a a'.

The pistons P P consist of a disk of rubber, held between the two caps p p, the lower one of which has a stem, s, passing through the rubber. The upper end of this stem has a screw-thread to receive the nut T, and thus hold the upper cap and compress the rubber at pleasure. The stem also has a female screw to receive the lower end of the piston-rod K. By this construction the piston is complete 80 in itself, and when worn may be removed and replaced by a new one, or the piston-rod K may be removed and replaced by a longer or shorter one at pleasure.

The supply-valves R R' and the discharge-valves S S' are made with a metallic valve-seat, s, or disk of metal, corresponding to the bottom of the cylinders, and placed between two pieces of leather packing. These valve-seats and the bottoms of the cylinders are 90 packed by the action of the single nut I pressing down upon the cap H on the top of the cylinders.

The motion of these valves and the direction in which the water flows will be fully understood by the dotted lines and the arrows on the drawings.

We prefer double ball-valves, (shown in Figs.

5 and 6,) as these allow a longer stroke to the piston and are more easily made and repaired. We make two plates or valve-seats, V V', and attach baskets *g* thereto, as shown in Fig. 6, 5 and then insert the balls into the baskets through the holes in the plate. Two smaller holes, *h*, serve as the valve-seats when the two plates are brought together, as shown in Fig. 5, the packing *U* being placed between 10 the plates V V'.

The castings in our pump require very little fitting or machine work, and we save the expense of the ordinary screw-bolts, the single nut *I*, on the central discharge-pipe, and the 15 cap *H* uniting the different parts at a single operation, and making the valves easily accessible for repairs, if necessary.

The manner of attaching the lever to the air-chamber and the arrangement of all the 20 parts make our pump very compact as a whole.

If desired, a single handle may be inserted vertically in the socket *Z*, for working the pump.

Having described our invention, what we 25 claim is—

1. The double-way pipes A A' and B B',

cast in one piece and forming inverted arches having hubs *a a'* to receive the valve-seats, packing, and lower ends of the cylinders F F', and coupled centrally to the pipe C below and the pipe G above, substantially as set forth.

2. The nut *I* and cap *H* on the discharge-pipe G, for fastening the cylinders F F', substantially as described.

3. In a combined suction, submerged, and 35 force pump, the combination of the double-way pipes A A' B B' with the pistons and piston-cylinders and the piston-rods K, inserted into the stem *s*, and having guides in the cap *H*, substantially as set forth.

4. The two plates or valve-seats V V', with 40 the packing *U* between them, said plates having a larger hole or holes, through which the ball is inserted into the basket *g*, and a smaller hole or holes, *h*, substantially as set forth.

In testimony whereof we affix our signatures in presence of two witnesses.

GEO. F. BEEBE.
WALTER O. BEEBE.
